UNITED STATES PATENT OFFICE

HANS ALBERT PHILIPS, OF STRATFORD, CONNECTICUT, ASSIGNOR TO THE AMERICAN FABRICS COMPANY, OF BRIDGEPORT, CONNECTICUT, A CORPORATION OF CONNECTICUT

WATERPROOF SWEATBAND STRUCTURE

Application filed August 10, 1929. Serial No. 384,817.

My invention relates to hats, caps and the like and has for an object to provide an improved sweatband structure therefor, adapted to prevent perspiration from penetrating 5 into the body of the hat and discoloring the same.

Although hats have heretofore been provided with waterproof linings they have failed to exclude perspiration because the 10 sweatband proper, or "leather", as it is called, has been sewn to the lining and the lining has been sewn to the hat, with the result that stitch holes were formed in the lining through which perspiration could make its 15 way.

It is an object of the present invention to provide a waterproof lining in which stitch holes are closed by means of waterproofing material so that there is no possibility of 20 leakage through the waterproof lining material.

Another object of my invention is to provide a sweatband structure comprising a lining strip and a "leather" permanently attached together with a waterproof joint therebetween, which structure may be sold as an article of manufacture to be applied to hats. The present invention is a modification of 25 that disclosed in my copending application 20 Serial No. 384,816, and filed concurrently herewith.

Other objects and advantages of my invention will appear in the following description of a preferred embodiment and thereafter 35 after the novelty and scope of the invention will be pointed out in the claims.

In the accompanying drawing;

Figure 1 is a fragmentary view of a hat partly broken away and in section, showing 40 my improved sweatband structure applied thereto; and

Fig. 2 is a view in section of a portion of the sweatband structure on an enlarged scale.

In Fig. 1, I have used the reference number 45 10 to indicate a hat. This is provided with the usual hat ribbon 11 which covers the attachment of the sweatband structure to the hat. The usual hat leather is indicated at 12. Although this is referred to as a 50 "leather", it will be understood that the term

is a technical one applied to the sweatband proper and should not be considered as limiting the invention to sweatbands of leather, for obviously other materials might be used. Between the leather and the hat is inserted 55 a lining consisting of a strip 13 of waterproofed fabric cut on the bias so that it may stretch to conform to the curvature of the hat and also to permit of belling or flaring the lower edge of the sweatband. The strip 13 is wrapped about a reed 14 so as to form a bead 15 at the lower edge of the sweatband structure. The strip 13 extends beyond the point where it is wrapped about the reed to 60 form an upstanding attaching flap 16. 65

The leather and lining are fastened together by means of stitching 17 close to the reed 14, the stitching being preferably of the type which will bind the lower edge of the leather to the lining. It will be observed that 70 this stitching passes through both the main body of the strip 13 and the upstanding flap 16, and consequently holes are formed directly through the lining material through which perspiration could pass. However, to 75 prevent such passage of perspiration, I apply waterproofing material 18 to the outer surface of the flap 16 over the stitching 17; also, to prevent seepage of moisture through the stitching and thence between the flap 16 and the main body of the strip 13, waterproofing material 19 is inserted, after the parts have 80 been stitched together, between the flap and strip 13. This completes the sweatband structure which may now be applied to a hat by 85 merely sewing the flap 16 to the hat, as indicated at 20 in Fig. 1. Thereafter, the ribbon 11 is slipped over the sewing so as to conceal the same. 90

It will be observed that by this arrangement, I provide an article of manufacture which may be furnished to hat manufacturers and may be applied by unskilled labor without any precautions against injuring the waterproof qualities of the lining. 95

Having thus described my invention what I claim as new and desire to secure by Letters Patent is:

1. A waterproof sweatband structure, 100 comprising a strip of waterproof material

folded at its lower edge to form an upstanding attaching flap at one side of the strip, a leather at the other side of the strip and stitched thereto at its lower edge, the stitches passing through the main body of the strip and the flap, and waterproof material applied over the stitching on the outer face of the flap; and also between the flap and the main body of the strip above the stitching.

10. 2. A waterproof sweatband structure, comprising a strip of waterproofed fabric folded at its lower edge to form an upstanding flap at one side of the strip, a reed in the fold of the strip, a leather against the other side of the strip and stitched thereto, the stitches passing through the main body of the strip and the flap close to the reed, and waterproof material applied to the outer face of the flap over the stitching and also between the flap and the main body of the strip above the stitching.

In testimony whereof, I have signed this specification.

25 HANS ALBERT PHILIPS.
